PISTON EXPANDER

Harold K. Switzer, Newport, Ky.

Application August 3, 1940, Serial No. 350,426

4 Claims. (Cl. 80—5)

This invention relates to the art of expanding or reshaping pistons which are of improper size. In the operation of internal combustion engines the pistons may become collapsed or misshapen due to the repeated expansion and contraction to which they have been subjected over a period of time under varying temperature conditions. The looseness which results from the collapse and distortion of the piston is objectionable for several reasons. The efficiency of the engine is substantially decreased by pistons of improper size or shape and the objectionable piston "slap" commonly heard in older engines, is a characteristic symptom of the defect.

This invention is particularly directed to a simple, inexpensive hand tool for expanding pistons by rapid and easy manipulation of the tool relative to the piston. A method of expanding pistons in which this tool may be utilized is fully described and claimed in my United States Patent No. 2,289,941 of July 14, 1942. Heretofore, complex peening machines have been utilized for the reshaping operation. It has been necessary to dismantle the engine and remove the pistons from it before they could be operated upon in the peening machine, and the entire job is both expensive and tedious.

In contrast, the principal object of the present invention has been to provide a very simple tool with which the pistons can be operated upon, reshaped and expanded while they are in the engine or after they have been removed from it.

Briefly, the present invention contemplates a tool by means of which the material of the piston skirt is contacted under pressure along a series of lines extending longitudinally of the piston skirt. The metal of the skirt along these lines of pressure contact is swaged, and peculiarly the piston is thereby expanded. In a typical expanding operation, the portion of the skirt opposite the thrust side of the piston is worked upon to accomplish the reshaping of it; however other parts of the piston also may be treated for other reshaping or expanding purposes.

For use in the practice of the method described and claimed in my aforesaid patent, this invention contemplates a simple and inexpensive tool which may be employed satisfactorily by an ordinary automobile mechanic. This tool includes a pair of hardened metal wheels. One of the wheels is flat peripherally and is of substantial width. The other may be relatively thin and the periphery may be rounded. The two wheels are arranged to cooperate with one another to exert a

swaging action upon the metal of a piston skirt placed therebetween.

The tool normally is used so that the thin wheel rests on the interior surface of the piston skirt, and a handle is provided for the tool so that the wheels may be moved along lines longitudinally of the skirt to compress the metal; it is this operation which expands the skirt circumferentially.

10 Except in extraordinary instances the tool is used to operate upon the pistons without dismantling them from the engine block, for instance with the oil pan and the connecting rod bearings removed the piston which is to be operated upon is drawn downwardly to a point at which the skirt of it is disposed beneath the block; the skirt is now accessible and readily may be reshaped and expanded.

15 The tool may be used with substantially all types of pistons, for instance those made of cast iron and semi-steel as well as those made from aluminum alloys. The operation of expanding or reshaping a piston requires but a fraction of the time required by past methods.

20 25 For use in conjunction with the tool, an object of the present invention also has been to provide a shield adapted to be fitted around the piston skirt so as to keep the outer roller of the tool from marring the metal surface as the reshaping operation is performed. In the use of such a protector the major swaging action is accomplished by the thin wheel at the interior of the piston. In other instances it is also practiced, by means of the present improvement, to expand the piston to an oversize dimension and then machine it back to size as in a lathe.

In the drawings:

20 30 35 Figure 1 is a perspective view showing a piston in the process of being expanded by a hand tool made according to the present invention;

Figure 2 is a fragmentary cross sectional view taken on a line through the piston skirt at the point where the tool is acting;

40 45 Figure 3 is a side view of the hand tool shown in Figure 1 wherein the details of construction are shown in cross section;

Figure 4 is a perspective view of a guard which may be utilized to protect the piston against marring by the tool;

Figure 5 is a fragmentary cross sectional view taken longitudinally through the piston;

Figure 6 is a view similar to Figure 5 in which the tool has been modified slightly to accommodate a piston having a strengthening ridge run-

ning around the inside of the piston near the lower edge of the skirt;

Figure 7 illustrates a modified form of the tool in which a stationary swage block is utilized in place of the thinner roller;

Figure 8 is a cross sectional view taken on line 8—8 Figure 7, further illustrating the modification.

Figure 9 is a diagrammatic cross sectional view taken laterally through one of the cylinders of an internal combustion engine illustrating the manner in which a piston may be expanded without removing it from the cylinder.

Figure 10 is a cross sectional view taken on line 10—10 of Figure 9.

In the drawings the piston shown is a relatively typical aluminum alloy piston having a T slot in its skirt. The use of the tool with other types of pistons will be discussed at a later point in the description. The thin-walled portion of the piston, termed the skirt, is indicated at 15.

The tool illustrated in the drawings, comprises two arms 16 and 17. The arms are secured to a bracket 18 by nuts which engage threaded portions 19 extending through holes in the bracket from the ends of the arms. The arms extend substantially parallel to one another from the bracket. The bracket is bent downwardly at an angle to the arms, as at 20, and is secured to a handle 21 by a screw or other means.

A pair of wheels 22 and 23 is mounted in slots in the ends of the arms respectively. The wheels are journaled on pins 24 press fitted in appropriate holes in the respective ends of the brackets. One of the wheels, indicated at 22, is narrow and rounded peripherally while the other, indicated at 23, is wide and flat peripherally.

Medially of the length of the arms means is provided for adjusting the arms toward and from one another. The adjustment means comprises a screw 25 which is threaded into one of the arms and locked therein by a threaded collar 26. The screw extends at right angles to the arm and passes through a hole in the other arm. Beyond the second arm the screw is engaged by a thumb nut 27. Thus, by tightening the thumb nut the two arms are drawn together. A slight flexing or springiness in the arms 16 and 17 aids materially in producing a smooth operation of the tool.

A shield 28, shown in Figure 4, comprising a thin sheet of spring steel may be utilized to keep the outer wheel from marring the outer surface of the piston. The shield is placed around the skirt of the piston and is retained in place by its own spring action. In most instances, the shield is not necessary though it may be used as a special precaution against marring the surface of the piston.

Operation

The expansion operation may be performed, as has been the practice heretofore, by removing the piston from the cylinder. In this instance, the piston is clamped or held head down on the work bench. When used on aluminum alloy types of piston, the wheels are first rolled up and down the skirt on both sides of the slot as near the pin bosses as is practical. The wheels should be rolled longitudinally of the piston in straight lines, with the thinner wheel on the inside of the piston. After each stroke, the tool is moved nearer the slot. It is only necessary to swage an area of approximately $\frac{3}{8}$ of an inch from each pin boss. Five or six strokes of the tool are thus sufficient to expand the piston about four to six

one-thousandths of an inch. The tool should be adjusted so that the wheels exert only a light squeezing pressure on the metal of the piston skirt since it is not necessary or desirable to gouge the metal to expand pistons by this method.

This same procedure may be used on semi-steel pistons as well as other aluminum pistons, that is, swaging the skirt of the piston near the 10 pin bosses on the side opposite the one subjected to thrust.

Cast iron pistons react somewhat differently to the swaging action of the method than do aluminum alloy pistons. Cast iron expands beneath 15 the wheels; bowing out where the wheels are rolled. Cast aluminum pistons expand at the slot, that is, the collapsed section of the skirt near the slot is reshaped by swaging the areas on both sides of the slot adjacent the pin bosses. 20 Cam ground pistons which have become rounded through use may be reshaped by swaging the metal of the skirt in these same areas, that is, near the pin bosses. This causes the cam ground piston to reassume its slightly oval shape. To 25 reshape a cast iron piston, the wheels are rolled over the skirt in the area directly opposite the center of thrust. Cut-away skirt pistons or "slipper" pistons made of cast iron are also reshaped by this latter method of employing the 30 tool.

Certain pistons having a rib around the inside of the piston below the pin bosses require a slightly modified tool, (Figure 6). In this instance the thinner wheel is journaled off-center 35 of the arm so that the arm clears the rib. Referring to Figures 7 and 8, a modified form of the thin swaging wheel is shown. Here a swage block 29 is substituted. The block is secured in a slot in the end of one of the arms, by a pin 30. 40 The operating surface of the block comprises a rounded ridge 31 similar to the rounded peripheral ridge of the thin swaging wheel.

A practical advantage of considerable importance provided by the present invention is that 45 pistons may in many instances be expanded without removing them completely from the cylinders. The manner in which this is accomplished is disclosed in Figures 9 and 10. This practice is not applicable in the cases of V-type or radial engines. To prepare the piston, the oil pan and the connecting rod bearings are removed. The piston to be treated is then pulled down to expose the skirt and the connecting rod and crank-shaft are moved to one side as shown in Figure 50. 9. In most engines, the piston can be brought down to rest on the throws of the crankshaft as shown. The expanding operation can then be carried out as described above. The piston may be slipped back up into place to check the fit 55 as the expanding operation proceeds.

In some cases, the handle of the tool interferes with the operation of the tool because of 60 obstructions. In these instances, the handle can be reversed by changing the position of the arms 16 and 17.

It is very simple to use the tool to expand a piston regardless of whether the piston be entirely removed from the cylinder or be permitted to remain partially in the cylinder during the 65 making of the repair. The tool is susceptible to use on practically every type of piston, and by skillful and judicious use of it, the piston skirt may be squeezed or thinned to the desired degree, thus creating compensatory expansion of 70 the piston skirt so that it better fits the cylinder. 75

Having described my invention, I desire to be limited only by the following claims:

1. In a piston expanding tool having a handle and a pair of spaced arms adapted to straddle a piston skirt carried by said handle, cooperative metal swaging elements carried one by each of said arms; one of said metal swaging elements comprising a rotatable roller having its axis crosswise to the arm by which it is carried and a narrow rounded tread for engaging the piston 10 surface.
2. In a piston expanding tool, a pair of arms spaced apart and connected adjacent one of their respective ends, a metal displacing element carried by each of said arms, said elements being adapted to engage the skirt of a piston on opposed sides thereof; one of said elements comprising a rotatable roller having a narrow rounded tread journalled in the end of an arm with its axis positioned crosswise thereto.
3. In a piston expanding tool a pair of arms spaced apart and adapted to straddle a piston skirt, a rotatable roller journalled in the end of each of said arms with its axis transverse thereto,
- 5 said rollers being adapted to exert a squeezing action on the piston skirt, one of said rollers having an outwardly tapered tread for the displacement of the metal in the piston skirt, the other of said rollers having a substantially flat tread for supporting the portion of the skirt opposite to that with which the first named roller is engaged during the metal displacement operation.
- 10 4. In a tool for expanding a piston by swaging the skirt of the piston along lines extending longitudinally of said skirt, a pair of spaced arms adapted to straddle a piston skirt, a swaging element carried by each of said arms, one of said 15 swaging elements presenting a narrow tread surface for displacement of the metal in the piston skirt upon engagement therewith, the other of said elements being rotatable on an axis crosswise to the arm by which it is carried and being adapted to cooperate with the first named element in supporting the piston skirt for engagement by said first named element.

HAROLD K. SWITZER.
